MILTON FISK, OF SPARTA, TENNESSEE.

Letters Patent No. 84,348, dated November 24, 1868.

—
HORSE-POWER
—

The Schedule referred to in these Letters Patent and making part of the same.

To all whom it may concern:

Be it known that I, MILTON FISK, of Sparta, in the county of White, and State of Tennessee, have invented a new and improved Horse-Power; and I do hereby declare that the following is a full, clear, and exact description thereof, which will enable those skilled in the art to make and use the same, reference being had to the accompanying drawings, forming part of this specification.

This invention relates to improvements in horse-power apparatus, and has for its object to simplify and cheapen the construction of the same, and more especially to adapt them for driving grinding-mills.

It consists in the arrangement of a table, to be moved around the vertical axis of a fixed bed by the horse, said movable table carrying a counter-shaft and gearing deriving motion from a wheel secured to the fixed bed, and communicating it to a central spindle, which may serve as the spindle of a set of stones on the top of the movable table, or as a shaft for conveying motion to other machinery when the upper stone is removed and another section of shaft coupled thereto.

Figure 1 represents an elevation of my improved apparatus, partly in section;

Figure 2 represents a plan view; and

Figure 3 represents the adaptation of a millstone to the spindle.

Similar letters of reference indicate corresponding parts.

A represents a circular bed, preferably supported on posts, upon which the wheel B is secured, having internal teeth and a smooth upper edge.

C and C' represent a movable table, to be operated by the horse or other animal, and supported on a central spindle, D, resting at its lower end on the adjusting-lever E.

The said table is provided with a counter-shaft, F,

which derives rotary motion from the wheel B, and communicates it to the spindle G by suitable wheels.

H represents the bed-stone of a grain-grinding mill, which may be set in the top, C, of the table, and through which the point of the spindle projects, and is arranged to receive and communicate motion to an upper stone, as represented in fig. 3, or when the stone is removed, a socketed section of a shaft, I, may be applied to convey motion in any suitable manner, as, for instance, by a horizontal shaft, K, for the propulsion of other machinery.

The spindle G is set in a step on the adjusting-lever L, for the purpose of adjusting the running-stone with reference to the bed-stone, and the object of setting the spindle D upon an adjusting-lever is to regulate the position of the table C with reference to the face of the wheel B, to prevent too much friction thereon.

A meal-box may be set in the vacant space between the parts C and C' of the movable table, for the reception of the meal from the grinding-stones.

I claim as new, and desire to secure by Letters Patent—

1. The table C C' arranged as shown, and provided with the adjustable spindles D and G, and the operating-shaft F, and its wheels, in combination with the wheel B and bed A, all substantially as and for the purpose described.

2. The combination, with the movable table C C' and spindle G, of bed-stone H, substantially as and for the purpose described.

3. The combination, with the spindle G, of the socketed shaft I, substantially as and for the purpose described.

MILTON FISK.
